UNITED STATES PATENT OFFICE.

FERDINAND ABRAHAM, OF BOSTON, MASSACHUSETTS.

DESIGN FOR A TOBACCO-PIPE.

SPECIFICATION forming part of Design No. 29,326, dated September 13, 1898.

Application filed August 8, 1898. Serial No. 688,111. Term of patent 3½ years.

To all whom it may concern:

Be it known that I, FERDINAND ABRAHAM, a citizen of the United States, residing in Boston, county of Suffolk, State of Massachusetts, 5 have invented and produced a new and original Design for Tobacco-Pipes, of which the following is a specification, reference being had to the accompanying drawings, showing a part thereof, in which—
10 Figure 1 is a side elevation of my tobacco-pipe; Fig. 2, a front elevation of the bowl, and Fig. 3 a top plan view to show the shape of the mouthpiece.

The bowl of the pipe is substantially globular at its base. Its body, projecting vertically upward from said base, has its outer wall concaved cylindrically or curves inwardly equally throughout its circumference, flaring toward the mouth of the bowl. The 15 wall around the mouth is cylindrical in plan view, as shown in Fig. 3. From the globular bowl-base the stem-base projects laterally, rising vertically at an angle of about forty-five degrees, its outer end being capped with 20 a ferrule, as shown. The stem proper pro-

jects from this stem-base, being tapering toward said ferrule and flattened laterally at its outer end or mouthpiece, which portion is thus oval in cross-section. This flattened mouthpiece is separated from the taper portion by a boss, and the extreme outer end of 30 said mouthpiece is provided with a bead.

As shown in the plan in Fig. 3, the edges of the mouthpiece curve laterally inward and flare on a true curve to the end bead, where 35 said mouthpiece is of substantially the same width as at the beginning of the flattened portion adjacent the inner or central boss.

The leading features of my design are the cylindrical or circumferential concave or 40 groove in the bowl and the longitudinal inward curves in the edges of the mouthpiece.

What I claim is—

The design for a tobacco-pipe substantially as herein shown and described.

FERDINAND ABRAHAM.
